SANITARY SHOWER STALL

David A. Carlson, P.O. Box 168, Richfield, N.C.
Filed June 17, 1964, Ser. No. 375,705
18 Claims. (Cl. 4—146)

This invention relates to shower stalls generally, and, in particular, to shower stalls which can periodically clean the surface upon which the occupant thereof stands while taking a shower.

This invention has utility in connection with any shower stall; however, it is particularly useful in shower stalls which are to be used by the public. For example, when public shower facilities are located in bus and train stations, public parks and beaches, etc., for use by travelers, campers, swimmers, etc., maintaining the shower stall in a clean and sanitary condition is a constant problem.

A particular problem in this connection is the debris, such as soap wrappers, toothpaste tubes, food scraps, partially used bars of soap, etc., which will generally collect on the floor as the stall is occupied by successive users. Further, where the stall also serves as a dressing chamber, as can the shower stall shown in my copending patent application Serial No. 233,214, filed on October 26, 1962, entitled Sanitary Shower Stall, now Patent No. 3,132,350, there is the additional problem of laundry debris, such as wrapping paper, shirt stiffeners, etc., which will collect on the floor.

Therefore, it is an object of this invention to provide a shower stall which will periodically remove the debris and foreign material which has collected on the floor thereof.

Another object of this invention is to provide a shower stall which will push the foreign material which has collected on the floor, laterally off the floor.

Another object of this invention is to provide a shower stall which will move the foreign material deposited on occupant supporting surface of the floor laterally to a point remote therefrom where it can be collected for removal while the shower stall is unoccupied.

In many cases the foreign material may include items such as soap, candy, chewing gum, etc., which may tend to stick to the floor. Therefore, it is another object of this invention, and one of its important features, to provide a shower stall which will push the foreign material laterally off the floor, while concomitantly directing a jet of fluid against the foreign material to help move it off the floor.

These and other objects, advantages, and features of the invention will be apparent to one skilled in the art from a consideration of this specification, attached drawings and appended claims.

These and other objects are obtained, in accordance with this invention, by providing a shower stall with means for moving the foreign material, deposited on the occupant supporting surface of its floor, laterally to one side of the floor where it may be collected for removal. In this manner, the floor of the shower stall can be cleaned while the stall is unoccupied to provide a clean floor for the next occupant. In one embodiment of the invention, in addition to moving the foreign material laterally to the side of the floor, it is carried to a point remote therefrom and deposited in a receptacle provided therefor. In another embodiment, a plurality of nozzles are provided to direct jets of fluid across the surface being cleaned concomitantly with the moving of the foreign material laterally therefrom.

The invention will now be described in connection with the attached drawings in which:

FIG. 1 is a horizontal sectional view through a shower stall illustrating an embodiment of the invention in which

2

a member is moved laterally across the surface of the floor, upon which the occupant of the shower stall stands when it is in use, to thereby push the debris or foreign material on the occupant-supporting surface, laterally toward the edge of the floor; this embodiment being further provided with fluid jets for improving the efficiency of the cleaning operation;

FIG. 2 is a partial sectional view taken along line 2—2 of FIG. 1 showing a side view of the member which moves across the surface of the floor to push the debris therefrom and the relative positions of the fluid jets located around the periphery of the floor;

FIG. 3 is a partial vertical sectional view of the shower stall illustrating an alternate embodiment of this invention wherein an endless belt is adapted to move fingers through slots in the floor of the shower stall, to move the debris thereon laterally to one side of the floor, and to carry it to a point remote from the floor where it is deposited in a receptacle;

FIG. 4 is a fragmentary isometric view of the floor of the embodiment in FIG. 3 illustrating the fingers in position to move through the slots provided therefor in the floor;

FIG. 5 is a plan view of a floor similar to that shown in FIG. 4, wherein the floor is covered with a layer of flexible material to make it more comfortable for the occupant of the shower;

FIG. 6 is a partial sectional view through the floor of FIG. 5;

FIG. 7 is a partial vertical section through a shower stall equipped with yet another embodiment of this invention where the floor is pivotally mounted to move between an occupant supporting position and a generally vertical position to move the foreign material thereon laterally to the side of the floor; and

FIG. 8 is another view of the embodiment shown in FIG. 7 showing, how the debris collecting means located on the side of the floor to receive the foreign material which falls from the floor when it is moved to the generally vertical position shown, can be moved upward to further clean the floor where both the floor and the debris collecting means are made up of a plurality of spaced, parallel fingers.

In the embodiment shown in FIGS. 1 and 2, the shower stall, generally indicated by the number 10, is provided with double-walled, hollow, side walls 11, 12, 13 and 14, a bottom 15 and a floor 16, spaced above the bottom and having an occupant-supporting surface 17. Floor 16 is supported by sidewalls 11, 12 and 13 but extends only part way toward wall 14, its back edge 16a (shown by the dotted line in FIG. 1) stopping adjacent the edge of grate 18 which covers the drain (not shown). The drain provides an outlet for the water used in the shower and floor 16 and bottom 15 are preferably slanted toward the drain.

The lower edge 14a of the inside portion of side wall 14, as shown in FIG. 1, curves outwardly to a point above the floor adjacent edge 16a. This is done to keep the occupant of the shower from inadvertently stepping off the floor onto grate 18. Preferably the grate is below the level of floor 16 to provide sufficient storage space for the debris which is collected thereon so that it will not have to be cleaned out too frequently.

In accordance with this invention, means are provided to move the foreign material or debris deposited on surface 17 laterally to one side of the surface. In the embodiment shown, a cleaning member 20 extends across surface 17 and is connected at each end to piston rods 21 and 22. The piston rods are, in turn, connected to pistons (not shown) within double acting cylinders 23 and 24 which extend through rear wall 14 of the shower stall. Then, by applying hydraulic or pneumatic pres-

sure to the cylinders, cleaning member 20 is moved by the pistons in the cylinders and the connecting rods, from its position adjacent front wall 12, as shown in FIG. 2, laterally across occupant-supporting surface 17 of the floor toward grate 18, pushing ahead of it any foreign material which has been deposited on the surface. By moving the cleaning member past edge 16a off the floor all of the foreign material it has pushed ahead of it will be deposited on grate 18 and the floor will be cleaned of debris and ready for the next occupant.

Means are provided to return the cleaning member to its position adjacent wall 12 after the cleaning operation is completed. In this embodiment, this is done by cylinders 23 and 24 which are of the double-acting type. Thus by reversing the side of the pistons against which the fluid pressure acts, the cleaning member will be returned to the position shown in FIG. 2. If desired, resilient means can be employed for this same purpose.

As shown in the drawings, member 20 is what is commonly known as a "squeegee," having a relatively rigid body 20a to which is attached a flexible member 20b. The flexible member is usually made from an elastic material such as rubber, which will not only push foreign material ahead of it as it moves across the floor but will also remove the excess water thereby allowing it to dry faster after the shower has been used.

Instead of a squeegee as shown, a more rigid member could be used with an edge designed to scrape surface 17. This would insure that all foreign material, even chewing gum, etc., would be freed from the surface and carried to the drain. Or, if desired, a brush could be substituted for squeegee 20 to provide a sweeping action to push the material ahead of it as it moves across the surface.

To protect member 20 while it is not being used and the shower is occupied, front wall 12 is provided with a ledge-like portion 12a which extends outwardly from wall 12 over member 20 when it is in the position shown in FIG. 2. In this way the occupant of the shower will be prevented from inadvertently stepping on member 20, or otherwise damaging it while he is in the shower.

Since it is likely that some of the foreign material deposited on surface 17 by an occupant of the shower will be of a sticky nature, such as candy, mints, chewing gum, etc., means are also provided to wash the floor concomitantly with the exerting of a lateral force on the material by the cleaning member urging it toward the drain.

Thus, in the embodiment illustrated in FIGS. 1 and 2, a plurality of nozzles 26 are located around the periphery of the floor and positioned to direct a stream of fluid against surface 17 which will tend to wash any material thereon laterally toward drain 18. Supplying nozzles 26 with a pressure fluid is a common header 27 which is located in the hollow portion of sidewalls 11, 12 and 13.

The washing action of the nozzles can be employed either concurrently with the movement of cleaning member 20 across the surface of the floor or the washing action can occur before or after the movement of member 20. Preferably the washing action occurs before the movement of member 20 so that it will exert its positive lateral force on the foreign material on the floor after the material has been at least partially loosened by the action of the jets.

As shown in FIG. 2, the nozzles in wall 12 are located in ledge portion 12a which extends outwardly over cleaning member 20 so the fluid jets they emit can flow unimpaired directly across surface 17 to the drain while the cleaning member remains under the ledge.

It will be necessary, of course, to periodically clean out the foreign material which is collected in drain 18. This can be conveniently done by providing a door (not shown) in rear wall 14 which will permit access to the grate through the rear of the shower.

An alternate embodiment of the invention is shown in

FIGS. 3 through 6. In this embodiment the shower stall, generally indicated with the number 30, is provided with a bottom 31 in which the drain (not shown) is located, an outer back wall 32 and an inner back wall 33. Spaced 5 above bottom 31 is floor 34 for supporting an occupant of the shower, comprising a plurality of spaced-apart elongated members 35 which are cantilevered out from support member 31a attached to the bottom of the shower. By spacing members 35 apart a plurality of open-ended slots 36 are provided in the floor.

An endless belt 37 is mounted on rollers 38, only two of which are shown, to travel below floor 34 and up into chamber 41 formed by outer back wall 32 and inner back wall 33. Power means (not shown) are provided to drive 15 one of the rollers to move the belt during the cleaning operation. Attached to belt 37 and carried thereby are a plurality of fingers 39, which are spaced apart across the belt so that they will extend upward into slots 36 between elongated members 35 and travel through the slots as the belt moves below the floor.

Fingers 39 are pivotally attached to belt 37 so they can pivot in the direction of the travel of the belt, but they are provided with stop means 40 (as best seen in FIG. 6) which engage the belt and prevent the fingers from pivoting rearwardly beyond the position illustrated.

In this position, as the fingers move along open-ended slots 36 they will engage any foreign material which has been deposited on the floor by the occupant of the shower stall and carry it laterally off the surface of the 30 floor. As the fingers reach the end of open-ended slots 36, the endless belt will turn upward as is indicated by the dotted lines in FIG. 3 to cause the fingers to act as baskets in which the foreign material which they have moved laterally off the floor can be caught and carried 35 upward into the compartment between the two back walls. As the fingers reach the top of their travel in rear compartment 41 and start their downward trip, they will, of course, dump whatever material they are carrying. To catch this material for removal from the shower stall an 40 inclined baffle 42 is arranged to deflect the material falling from fingers 39 into storage compartment 43, where the material will be collected and from where it can be removed periodically as the need demands. Baffle 42 is provided with open-ended slots (not shown) adjacent 45 its upper end similar to slots 36 in floor 34 to allow fingers 39 to pass downwardly through the upper edge of the deflecting member after depositing the material they are carrying into the storage compartment.

As many sets of fingers as desired can be used. In 50 FIG. 3, nine sets are illustrated; however, one set would probably be sufficient to do the job adequately. Preferably the fingers in each set are arranged on the endless belt in alignment, as in FIG. 4, so they will move along slots 36 more or less as a unit. The width of slots 36 and members 35 and the number of slots provided can, 55 of course, be varied as required.

A slotted floor, such as the type employed in this embodiment, may be uncomfortable for the occupant to stand on. To make the floor more comfortable, a layer 60 44 of flexible material, such as rubber, may be placed on top of the floor in the manner illustrated in FIGS. 5 and 6. This will help bridge slots 36 between elongated members 35 and make the floor more comfortable to stand on. Then by providing the material with slits 65 45 located more or less midway between elongated members 35, members 39 can extend readily through slots 36 and perform their function as described above without any interference from the layer of flexible material.

Thus, when this embodiment is in operation, each time it is desired to clean the floor, the power means used to move belt 37 are energized and fingers 39 are moved along slots 36 to push the foreign material off elongated members 35, carry it to a point above receptacle 43 into which it is dumped.

Yet another embodiment of the invention is illustrated in FIGS. 7 and 8 of the drawings. In this embodiment instead of moving debris pushing apparatus along the surface of the floor to move the debris laterally to one side of the floor, the floor itself acts as the means for moving the debris to one side thereof.

Thus, as shown in the drawings, a shower stall, generally indicated by the number 50, is equipped with a U-shaped floor 51 having one leg 51a pivotally mounted above bottom 50a of the shower stall by shaft 52. This allows leg 51b of the floor to be moved from the position shown in FIG. 7, where it provides support for the occupant of the shower, to the position shown in FIG. 8, where it is generally vertical to allow any debris or foreign material, which was deposited on the floor while it was in use, to fall by gravity to one side of the floor.

Means are provided to move the floor between the two positions. In the embodiment illustrated a fluid operated cylinder 53 is mounted on the bottom 50a of the shower stall with its piston rod 53a pivotally attached to leg 51a at a point spaced from shaft 52. The operating lines for providing power fluid to cylinder 53 are not shown. Normally, these extend to a point outside the shower stall where they are connected to a source of pressure. Valves are then provided to control the flow of fluid to move the piston (not shown) which is located within the cylinder and attached to rod 53a, up and down as desired to move leg 51b between the two desired positions. To further support leg 51b when it is in its generally horizontal occupant supporting position, a support bracket 55 is attached to the wall of the shower stall to support the outer end of leg 51b when it is in this position.

Obviously, the movement of floor 51 to a vertical position, as shown in FIG. 8, will cause most of any foreign material or debris, that is left thereon by the occupant of the shower, to fall by gravity to one side of the floor. Preferably means such as grate 56, are also provided to catch the material which falls from the floor to allow it to be periodically removed and to keep it from collecting in drain 58.

Some foreign material such as, soap bars and candy wrappers, which may be dropped, could stick to the floor and not fall to grate 56 when the floor is moved to its vertical position. To help remove this type of debris, means are provided to push this debris to one side of the floor much in the same manner as was done in the previously described embodiments.

Thus, in the embodiment illustrated, floor 51 comprises a plurality of U-shaped fingers, which are arranged in spaced parallel position to provide a slotted floor like that of the embodiment in FIGS. 3-6, upon which the occupant of the shower can stand. With this arrangement, when pressure cylinder 53 moves leg 51b of the floor to its vertical position, the slots in between the individual fingers of the floor are located above the individual fingers which make up grate 56. Then, by moving grate 56 upward through the slots between the fingers by means of pressure cylinder 57, the debris or foreign material which is adhering to the fingers to the extent that it will not fall therefrom, will be removed by the grate. Afterward, the floor can be returned to its occupant supporting position as shown in FIG. 7 and the grate lowered back down into position to again be moved through the slots of the floor, also shown in FIG. 7.

This movement of grate 56 through the slots between the individual fingers of floor 51 is the same cleaning action as is obtained by fingers 39 as they move through slots 36 between the individual fingers 35 of the floor in the embodiment described above in connection with FIGS. 3 through 6.

If desired, a fluid-jetting system of the type described in connection with the embodiment of FIGS. 1 and 2 could be used along with the embodiments shown in FIGS. 3-8 to help keep the floor of the shower stall clean.

From the foregoing it will be seen that this invention is one well adapted to attain all of the ends and objects hereinabove set forth, together with other advantages which are obvious and which are inherent to the apparatus.

- It will be understood that certain features and sub-combinations are of utility and may be employed without reference to other features and sub-combinations. This is contemplated by and is within the scope of the claims.
10. As many possible embodiments may be made of the invention without departing from the scope thereof, it is to be understood that all matter herein set forth or shown in the accompanying drawings is to be interpreted as illustrative and not in a limiting sense.
15. The invention having been described, what is claimed is:
1. In a shower stall having a floor with an occupant-supporting surface, the improvement, in combination therewith, of means for cleaning the floor after the shower has been used and while the shower is unoccupied comprising means for pushing foreign material from the occupant-supporting surface and means for moving the foreign material pushing means parallel to the surface to remove foreign material therefrom while the shower stall is unoccupied.
2. The shower stall of claim 1 further provided with means for directing a stream of fluid across the occupant-supporting surface to help clean the surface of foreign material.
3. The shower stall of claim 1 in which the pushing means is a brush which sweeps the occupant-supporting surface as it moves laterally across it.
4. The shower stall of claim 1 in which the pushing means is a squeegee.
5. The shower stall of claim 1 in which the pushing means is provided with an edge for scraping the occupant-supporting surface as it moves laterally across it.
6. In a shower stall having side walls and a floor with an occupant-supporting surface, the improvement, in combination therewith of means for removing foreign material from the occupant-supporting surface while the shower is unoccupied, comprising, means located adjacent one side of the shower stall for collecting the foreign material, a member extending transversely across and engaged with the occupant-supporting surface, and means associated therewith for moving the member laterally across the occupant-supporting surface to push the foreign material on the surface into the foreign material collecting means while the shower is unoccupied.
7. A shower stall having side walls and a floor with an occupant supporting surface, said floor having a plurality of spaced, parallel, open-ended slots therein, means located adjacent one side of the shower stall for collecting foreign material, and means for moving through the slots in the floor to move foreign material on the occupant-supporting means laterally to the collecting means.
8. A shower stall having side walls and a floor with an occupant-supporting surface, said floor comprising a plurality of parallel, spaced fingers, means located adjacent one side of the shower stall for collecting foreign material, means pivotally mounting the floor for movement between a horizontal occupant-supporting position and a generally vertical position adjacent the foreign material collecting means, and means for moving the floor from the horizontal to the vertical position to allow any foreign material deposited on the fingers while in occupant-supporting position to fall by gravity onto the foreign material collecting means.
9. The shower stall of claim 8 in which the foreign material collecting means comprises a plurality of spaced, parallel fingers and means for moving the fingers between the fingers of the floor when the floor is in the generally vertical position to remove any foreign material lodged between the fingers of the floor.
10. A shower stall comprising side walls and a floor having a surface for supporting the occupant of the stall,

said floor having a plurality of laterally extending, parallel slots; a plurality of fingers located in the slots and means for moving the fingers through the slots to remove at least a portion of any foreign material deposited on the occupant-supporting surface.

11. The combination of claim 10 further provided with a layer of flexible material covering the occupant-supporting surface, and having an open-ended slit located above and parallel to each slot in the floor to accommodate the fingers as they travel through the slots.

12. A shower stall comprising, a floor having a surface for supporting an occupant of the shower, said floor having a plurality of elongated parallel slots open at, at least, one end; means movably mounted below the floor and equipped with a plurality of fingers arranged to extend through the slots above the occupant-supporting surface; and means for moving the fingers along the slots toward their open end to engage foreign material deposited on the surface and push it laterally off the surface.

13. The shower stall of claim 12 further provided with a receptacle and means for moving the fingers from the slots to a position above the receptacle to carry the foreign material removed from the occupant-supporting surface of the floor to the receptacle.

14. The combination of claim 13 further provided with a layer of flexible material on the occupant-supporting surface having slits through which the fingers can extend and travel.

15. In a shower stall having a floor with an occupant-supporting surface thereon, the improvement, in combination therewith of means for removing foreign material from the occupant-supporting surface when the shower is unoccupied, comprising, a member for pushing foreign material from the occupant-supporting surface, means for supporting the member in engagement with the occupant-supporting surface and to move the

member laterally across the surface to push any foreign material thereon off the surface.

16. The shower stall of claim 15 further provided with means for directing a stream of fluid across the occupant-supporting surface of the flow concomitantly with the movement of the member.

17. A shower stall comprising side walls and a floor for supporting an occupant of the shower, said floor having a plurality of spaced, parallel, fingers pivotally mounted to move from a generally, horizontal, position to support an occupant of the shower to a generally, vertical, position to allow any foreign material deposited on the fingers by an occupant to be carried laterally to the side of the floor, and means for moving the fingers between the two positions to clean the floor.

18. A shower stall comprising side walls and a floor for supporting an occupant of the shower, said floor having a plurality of spaced, parallel, fingers pivotally mounted to move from a generally, horizontal, position to support an occupant of the shower to a generally, vertical, position to allow any foreign material deposited on the fingers by an occupant to be carried laterally to the side of the floor and means for collecting the material carried laterally by the fingers having a plurality of spaced, parallel fingers and means for moving the fingers vertically between the fingers of the floor when the floor is in its generally vertical position.
